A. BANGERT

COMBINATION TOOL

Filed Sept. 20, 1921

INVENTOR
Adolph Bangert
Max H. Ordman
ATTORNEY

UNITED STATES PATENT OFFICE.

ADOLPH BANGERT, OF UNION HILL, NEW JERSEY.

COMBINATION TOOL.

Application filed September 20, 1921. Serial No. 501,973.

To all whom it may concern:

Be it known that I, ADOLPH BANGERT, a citizen of the United States, residing at Union Hill, county of Hudson, and State of New Jersey, have invented certain new and useful Improvements in Combination Tools, fully described and represented in the accompanying specification and drawing, forming a part of the same.

This invention relates to an improvement in combination tools and has for its object to provide a tool unit which, while combining the useful elements of various tools constantly required in automobile work or the like, shall be simple in construction and operation and, therefore, economical in manufacture, durable, and highly efficient.

This invention also has for its object to provide a novel wrench construction as a part of such tool unit which shall be capable of easy and quick adjustment to the largest and smallest parts in automobile work or the like, and the construction of which wholly obviates the objectionable feature of give in wrenches of ordinary construction.

With these and other objects in view, my invention in a preferred embodiment will now be described in detail by reference to the accompanying drawing, in which similar reference characters denote corresponding parts and in which Figure 1 is a perspective view of the complete tool; Fig. 2 is a side elevation of one end thereof with the bail or hook shown in cross-section; Fig. 3 is a top plan view of the tool with the plier end shown in section; and Fig. 4 is a perspective view of a modified construction of the tool.

Referring now to the drawing the tool consists of two crossed members A, B pivoted at 10 and so shaped as to provide at one end of the tool jaws 1, 2 forming in effect a pair of pliers, and at the other end jaws 3, 4 to serve as wrench. One of the members, as A, for instance, is formed with a raised or thickened portion 5 having on its outer face a longitudinal row of notches or teeth 6. Pivoted to the sides of the opposite jaw 4 as at 7' is a loop-shaped member, bail, or hook 7 capable of being passed around the jaw 3 and provided centrally with a knife edge or tongue 8 which is adapted to engage any one of the notches or teeth 6. The notched or toothed portion 5 is suitably curved as shown and so situated with respect to the pivotal point

of the bail 7 that on shifting the bail from one end to the other of the curved surface 5 the jaws 3, 4 of the wrench will be opened or closed. Thus in the extreme forward position of adjustment of the bail the jaws 3, 4 of the wrench will be opened to their widest point, and when the bail is in its extreme rearward position said jaws will be either entirely closed or opened to the smallest width, according to the previously selected shape and size of said curved surface 5.

To facilitate adjustment and use of the wrench and pliers a suitable spring 9 is preferably mounted on the inner face of either one of the members A, B with its free end normally pressing against the other member and tending to separate the wrench jaws.

Each plier jaw may on its inner face be provided with cut-away notched portions 1', 2' to form pipe-engaging jaws. These plier jaws may be formed with the usual wire cutters 11.

When it is desired to use only the pliers or the tool elements associated therewith, the bail 7 is swung entirely off the jaw 3 of the cutter A.

In the modification shown in Fig. 4, which is the preferred construction, the jaw A' has its thickened cam-shaped portion provided with a longitudinal central slot 3^a extending throughout its entire thickness and length, and each lateral edge of said slot is toothed throughout its length, as at 6^a. The opposite jaw B' is provided on its inner face with a central longitudinally extending groove 4^a. The bail 7^a is in form of a lever, the lower end of which bears in the groove 4^a and is fulcrumed therein at 7^b. The upper end of said lever 7^a extends thru the slot 3^a of the jaw A' and has its free end broadened so as to form a cross-piece 7^c which in length corresponds with the width of the thickened or cam-shaped portion of the jaw A'. The lower edge of said cross-piece is formed to a knife edge or tongue 7^c which is adapted to cooperate with the two sets of teeth 6^a formed at the lateral edges of the slot 3^a.

The operation of this modified construction is the same as that of the first-described construction.

It is understood that various modifications may be made in the construction of the device without departing from the spirit

of my invention and I, therefore, do not restrict myself to the details described and shown.

What I claim is:—

- 5 1. In a wrench, a cam-shaped slotted jaw having two sets of teeth along the edges of said jaw, a second jaw having a groove, and a bail in form of a lever fulcrumed in said groove and adapted to project through a slot of the first-named jaw, the free end said lever being broadened and formed with a knife edge to cooperate with said two sets of teeth in the adjustment of said jaws relative to one another.
- 10 15. 2. A tool unit comprising pivoted crossed members, wrench jaws formed on said members, one of said jaws having a cam-shaped

outer surface and a slot extending through said jaw, two sets of teeth arranged along the edges of said slot, the opposite jaw having a longitudinal groove, and a lever pivoted in said groove and adapted to project through the slot in the other jaw, the outer free end of said lever being broadened and having a knife edge to engage said teeth, so that by swinging said lever from one end of the curved toothed jaw toward the other end, the jaws of the wrench will be adjusted to the desired extent.

In witness whereof, I have hereunto signed my name this 19th day of September, 1921.

ADOLPH BANGERT.
